ELECTRIC PLUG

Sami F. Shoucair, Beirut, Lebanon

Application September 7, 1948, Serial No. 48,104

2 Claims. (Cl. 173—361)

1

This invention relates to electric plugs, and more particularly to a two-wire appliance plug wherein the wires may be rapidly connected to the plug without the use of tools and without opening the plug.

A main object of the invention is to provide a novel and improved electric plug which is very simple in construction, wherein very little manual effort is required to connect the line wires thereto, and wherein a secure connection is made with said line wires.

A further object of the invention is to provide an improved electric plug wherein no tools or implements are required to connect the line cord wires thereto, wherein the line cord connections may be made rapidly and with only a small amount of manual effort, and wherein the line wires may be readily detached from the plug whenever desired, said plug being compact in size, cheap to manufacture, and rugged in construction.

Further objects and advantages of the invention will become apparent from the following description and claims, and from the accompanying drawings, wherein:

Figure 1 is a top plan view of an electric plug constructed in accordance with the present invention.

Figure 2 is a side elevational view of the electric plug of Figure 1.

Figure 3 is a longitudinal cross-sectional view taken on line 3—3 of Figure 2.

Figure 4 is a transverse cross-sectional view taken on line 4—4 of Figure 1.

Figure 5 is a transverse cross-sectional view taken on line 5—5 of Figure 1.

Figure 6 is an enlarged perspective detail view of a prong element employed in the plug of Figure 1.

Figure 7 is an enlarged perspective view of a plunger member employed in the plug of Figure 1.

Figure 8 is a fragmentary perspective view of the plunger member of Figure 7, shown in inverted position.

Referring to the drawings, the plug body is designated generally at 11. Said body comprises similar mating segments 12 and 13 of insulating material secured together by transverse bolt members 14, 14. The segments are formed with internal cavities 15 and are thickened at their forward marginal portions, as shown at 16, 16. Embedded in the thickened portions 16, 16 of segment 12 are the ends of a pair of prongs 17, 17. Said ends are formed with opposed projections 18 to improve the bond between the prongs and

the thickened portions 16, 16 of segment 12. The corresponding thickened portions of segment 13 are recessed to receive the exposed portions of the prongs when the segments are brought together in mating relationship. Each prong 17 has a rearwardly extending apertured lug element 19 for soldering a wire 20 thereto.

As shown in Figures 3 and 4, the segments 12 and 13 are each formed with vertically aligned 10 pairs of spaced internal lugs 21, 21 and 22, 22, which, when the segments are brought together in mating relation, define vertical guideways, as viewed in Figures 3 and 4. Between the said pairs of lugs 21, 21 and 22, 22 each segment is 15 formed with a projection 23, terminating in a semi-cylindrical recess 24. When the segments are brought together in mating relation, the recesses 24 define a bore axially aligned with the above described vertical guideways. Slidably positioned in said guideways are rectangular plunger blocks 25, 25 of insulating material, formed at their inner ends with circular recesses 26, in which are seated the ends of a coiled spring 27, which passes through the bore defined by the 20 recesses 24. Spring 27 biases the plunger blocks 25, 25 apart.

Each plunger block 25 has a square shank 28 which passes slidably through a square passage defined by mating channelled projections 29 in 30 the segments 12 and 13. Secured to the face of each block 25, adjacent its shank 28, is a knurled metal contact plate 30, the plate 30 and underlying face portion being counterbored around shank 28, as shown at 31, to receive the inner end 35 portions of the mating projections 29. Secured to the outer ends of the shanks 28, are push button elements 32. Secured to the respective segment surfaces, facing contact plate 30, are opposing knurled metal contact plate elements 33. The contact plate elements 33 of the segment 12 40 are connected to the respective prong lugs 19 by the wires 20, 20. The shanks 28 are formed with apertures 34, which may be brought into registry with opposed similar apertures formed in the projections 29 by pressing inwardly on the button elements 32, 32.

The mating rear marginal portions of the segments 12 and 13 are formed with grooved ribs 35, 35 defining passages 36, 36 for the line wires, shown at 37, 37. The passages 36, 36 terminate rearwardly adjacent the respective contact plates 30, 33 and are respectively in registry with the openings in the projections 29 associated with each set of contact plates 30, 33.

In connecting the line wires 37, 37 to the plug,

said line wires are inserted in the passages 36, 36 and pushed through said passages, the button elements 32, 32 being pressed inwardly to bring the shank openings 34 into registry with the openings in the respective projections 29. The wire ends pass between the respective sets of contact plates through the openings in the projections 29 and the openings 34 in shanks 28. When the button elements 32, 32 are released, the wire ends are gripped between the knurled contact plates 30, 33 by the expansive force exerted by spring 27 and are thereby securely connected to the plug.

To disconnect the line wires from the plug, the button elements 32, 32 are pushed inwardly and the wires are merely pulled out of the passages 36, 36.

While a specific embodiment of a quick-connectable electric plug has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A quick-connectable plug, comprising companion casing sections having main recesses and grooves in the meeting edges of the casing sections for receiving wires, means to detachably connect the casing sections, guide lugs arranged within the recesses and secured to the casing sections and having their inner ends spaced and arranged near the grooves, the guide lugs forming block guides, inner guide lugs arranged between the outer guide lugs and disposed within the main recesses and secured to the casing sections, the inner guide lugs forming a spring guide, insulating blocks slidable within the outer guides, a spring arranged between the insulating blocks and held within the inner guide and engaging the inner ends of the insulating blocks, outer metallic plates arranged within the casing sections adjacent to the grooves, inner metallic plates carried by the outer ends of the blocks and arranged in opposed relation to the outer plates to clamp the ends of the wires against the outer plates, rods connected with the blocks and extending to the exterior of the casing sections,

and metallic prongs carried by the casing sections and electrically connected with certain of the metallic plates.

2. A quick-connectable plug, comprising companion casing sections having main recesses and grooves in the meeting edges of the casing sections for receiving wires, means to detachably connect the casing sections, outer guide lugs arranged within the recesses and secured to the casing sections and having their inner ends spaced and arranged adjacent to the grooves, the guide lugs forming block guides, inner guide lugs arranged between the outer guide lugs and disposed within the main recesses and secured to the casing sections, the inner guide lugs forming a spring guide, insulating blocks slidable within the outer guides, a spring arranged between the insulating blocks and held within the inner guide and engaging the inner ends of the blocks, apertured outer metallic plates arranged within the casing sections adjacent to the grooves, apertured inner metallic plates carried by the outer ends of the blocks and arranged in opposed relation to the outer plates, rods connected with the blocks and passing through the apertures of the inner and outer plates and extending to the exterior of the casing sections, said rods having transverse openings to receive the ends of the wires which are clamped between the inner and outer plates, and metallic prongs carried by the casing sections and electrically connected with certain of the metallic plates.
